UNITED STATES PATENT OFFICE.

MARTIN J. ROBERTSON, OF LOUISVILLE, KENTUCKY, ASSIGNOR TO AMERICAN ELEVATOR AND MACHINE CO., OF LOUISVILLE, KENTUCKY.

INTERLOCK FOR ELEVATORS.

Application filed August 30, 1926. Serial No. 132,564.

This invention relates to an interlock for elevators and while it is especially designed for use in automatically controlled elevators operated by the public, it can also be used 5 to advantage with any electric elevator.

It is an object of the present invention to provide a means whereby the door of an elevator enclosure cannot be opened while the car is in motion and a further object is to 10 prevent the starting of the elevator car while any of the doors of the enclosure are open.

It is well known to those skilled in the art that while some devices have been provided for the purpose of preventing operation of 15 the doors of an elevator enclosure while the elevator car is in motion, such devices have been objectionable because it has been found, by exerting a constant pull upon a door in an effort to open it, said door will open the instant 20 the elevator car passes the particular door. This has resulted in serious accidents which it is an object of the present invention to avoid.

With the foregoing and other objects in 25 view which will appear as the description proceeds, the invention resides in the combination and arrangement of parts and in the details of construction hereinafter described and claimed, it being understood that changes 30 in the precise embodiment of the invention herein disclosed, may be made within the scope of what is claimed without departing from the spirit of the invention.

In the accompanying drawings, the preferred form of the invention has been shown.

In said drawings,

Figure 1 is a front elevation of the lock with the cover removed and the magnet being shown in section and a door locked in closed 40 position.

Figure 2 is a similar view showing the door unlocked.

Figure 3 is a side elevation of the structure, 45 portions of the doors being shown in section and a part of the housing of the structure being broken away.

Figure 4 is a diagram showing the wiring of the apparatus.

Referring to the figures by characters of 50 reference 1 designates a part of the elevator enclosure provided with the usual or any preferred forms of doors 2 for use at the different landings. To each door is connected a bracket 3 depending therefrom and carrying a lat-

erally extending tongue 4 constituting a keeper. This tongue is provided in the upper edge of its free end portion with ratchet teeth 5 while within the lower portion of its free end below the teeth is an inclined slot 6.

The elevator car, a portion of which has 60 been indicated at 7, is provided with an upwardly extending deflecting arm 8 constituting a cam.

Secured to the wall of the enclosure adjacent the path of the cam 8 is a housing 9 having an opening 10 in one wall thereof for the reception of the keeper 4 when the door 2 is closed as shown, for example, in Figure 1.

A pivot pin 11 is arranged within the housing 9 and has a pawl 12 mounted thereon with its head 13 so located as to engage one of the teeth 5 when the keeper is inserted into the housing 9. The pawl has a depending arm 14 adapted to receive thrust from a spring 15 interposed between said arm and one arm 16 of a lever 17 pivotally mounted on the pin 11. The other arm of this lever has a laterally extending bearing pin 18 adapted to work within a slot 19 in the housing 9 and the outer end portion of this pin has a wheel 20 journaled upon it. A spring 21 thrusts against lever 17 so as to hold the pin 18 normally at one end of the slot with the head 13 of the pawl 12 in its lowermost position and upward movement of the pawl 12 80 relative to the lever is limited by a stop finger 22 carried by the pawl and adapted to bear against the lever 17, as shown.

An electromagnet 23 is arranged in the housing and has an armature 24 from which is extended a pin 25 adapted to bear upon the pawl 12. This magnet is of sufficient strength to overcome the resistance of the spring 15.

A switch lever 26 is fulcrumed in the housing 9 and has a pin 27 extending from one end thereof slidably engaged by a contact plate 28. A spring 29 is mounted on this pin and bears against the plate. Separate contacts 30 suitably insulated from each other are arranged within the housing and are so located that when the lever 26 is moved in one direction the plate 28 will come against both contacts and connect them electrically.

One end portion of the lever 26 has a laterally extending roller 31 adapted to be received by the slot 6 in keeper 4 so that when the keeper is moved to the position shown, for example, in Figure 1, the roller 31 will be

shifted by the walls of the slot 6 so as to cause the lever 26 to move plate 28 to circuit closing position.

In Figure 4 the wiring of the invention has been illustrated in diagram. The motor for operating the elevator car has been indicated at 32, the control panel has been indicated at 33 and the switch on the elevator car has been indicated at 34. Lock housings 10 at two of the landings of the elevator shaft have been shown at 9. All of the contacts 30 are arranged in series with the movable switch element 35 carried by the car and forming a part of the car switch 34 so that the circuit is broken unless the plates 28 at all landings are in engagement with their contacts. This is only possible, of course, when all of the doors are closed. The leads or service wires have been indicated at 36 15 and 37. Separate magnetic switches are provided as indicated at 38 and 39, each switch being a doubled switch adapted, when closed, to complete a circuit through the motor as will be obvious. When one switch is closed, 20 however, the current flows in one direction through the motor whereas when the other switch is closed the direction of flow of the current is reversed. Thus the motor can be operated to move the elevator car upwardly 25 or downwardly.

The coil of the magnetic switch 38 is electrically connected to the lead 37 and to one contact 41 of the car switch. The other contact 42 of the car switch is electrically 30 connected to the coil of the other magnetic switch, said coil being indicated at 43 and being electrically connected to the lead 37.

The magnetic switches are normally open. It will be apparent, however, that when the 40 switch element 35 is shifted to engagement with the contact 41 a circuit will be completed from the lead 37 through coil 40 and thence through the contacts 30 and the plates 28 back to the other leads 36. The energizing 45 of the magnetic switch will cause a circuit to be completed through said switch 38 to the motor 32 so that the elevator car can thus be caused to move in one direction. By shifting the switch element 35 to engagement with the other contact 42 the other magnetic switch will be operated to drive the motor in the opposite direction. Obviously, however, the motor cannot be operated unless all of the doors are closed because it is essential that the circuit be completed between the contacts 30 and this is only possible when the plates 28 are in engagement with the contacts 30 at all of the landings.

When the circuit is closed to the motor 60 through the car switch the elevator car will travel in the selected direction and as it passes each landing a cam rail 8 movable with the car comes against the roller 20 at said landing and thrusts it laterally as indicated by 65 broken lines in Figure 1 and by full and

broken lines in Figure 2. As long as the current is flowing to the motor and the car is in motion, however, the magnet 23 remains energized as will be apparent and, therefore, the pawl 12 will be held against disengagement from the teeth 5. In other words the pawl will be retained in the position shown in Figure 1 although the wheel 20 can be thrust laterally by the cam rail against the action of the spring 21. Consequently 70 the door remains locked and cannot be opened. If, however, the elevator car is brought to a stop at any particular landing the magnet 23 will be de-energized as soon as the current to the motor is cut off and, therefore, the spring 15, which has been placed under compression by the lateral shifting of wheel 20 relative to the pawl 12, as shown by broken lines in Figure 1, will 75 promptly thrust against the arm 14 of the pawl 12 and cause the pawl to swing upwardly and release the tongue 4. The door at this landing can therefore be opened and the weight 45 provided at the upper end of the lever 26 will gravitate to break the connection at the contacts 30 as shown in Figure 2. Obviously it is now impossible to start the motor. However when the door is closed the recessed portion 6 of the tongue 4 comes against the roller 31 and swings the switch lever 36 so as to bring plate 28 against the contacts 30. At the same time the teeth 5 are brought to position under the pawl. When the car switch is closed so as to direct current to the motor, magnet 23 is promptly 80 energized with the result that pin 25 will be thrust against the pawl 12 and force it into engagement with the toothed tongue and there hold it so that the tongue cannot be withdrawn. This position will be maintained 85 as long as the magnet is energized and irrespective of the movement of cam rail 8 into contact with successive wheels 20 at the different floors or landings. If, at any time, a door should be left open at any point along the elevator shaft, it would not be possible to start the motor because the circuit would be broken at the contacts 30 as shown in Figure 2. It is necessary that all of the doors be closed before the car can be operated and it is necessary for a car to be at a selected landing and the current cut off before the door at that particular landing can be opened. The doors at the other landings cannot be 90 opened when the car is remote therefrom because the springs 21 hold the pawls 12 tightly in engagement with the teeth 5 of the tongues.

What is claimed is:

1. The combination with an elevator car 125 and an enclosure therefor having a door, of an electric motor for actuating the car, a switch adjacent the door for controlling the operation of the motor to bring the car to said door, a lock for fastening the door when 130

partly or entirely closed, means controlled by the flow of current to the motor for holding the lock against release of the door while the car is passing the door, means for releasing the locked doors upon failure of current, and cooperating means on the car and lock for positively unlocking the door when the car is at rest at the door with the motor circuit open.

10 2. The combination with an elevator car and an enclosure therefor having a plurality of doors, of an electric motor for actuating the car, a lock for fastening each door when partly or entirely closed, a switch adjacent each door for controlling the operation of the motor to bring the car to said door; a motor controlling switch on the car, means controlled by the flow of current to the motor for holding all of the locks against release of the doors while the car is passing the doors, cooperating means on the car and lock for positively unlocking any one of the doors when the car is at rest at said door with the motor circuit open and means for releasing the locked doors upon failure of current.

3. The combination with an elevator car, an enclosure door, an electric motor for actuating the car, of a magnetic switch remote from the car for controlling the flow of current to the motor, said switch being normally open, a car switch for closing the circuit to the magnetic switch to actuate the same, a lock for fastening the door when partly or entirely closed, a circuit closer constituting a part of the lock and included in the circuit with the car switch, cooperating means upon the door and the lock for maintaining the circuit closer in position to hold the circuit close to the car switch while the door is closed, said means cooperating to break the circuit when the door is opened, and electrically operated means for holding the door locking means in engagement with each other during the flow of current to the motor.

4. The combination with an elevator car, an enclosure door, an electric motor for actuating the car, of a magnetic switch remote from the car for controlling the flow of current to the motor, said switch being normally open, a car switch for closing the circuit to the magnetic switch to actuate the same, a circuit closer included in the circuit with the car switch, a lock casing adjacent the door, cooperating means upon the door and in the lock casing for maintaining the circuit closer in position to hold the circuit closed to the car switch while the door is closed, said means cooperating positively to break the circuit when the door is opened, cooperating means upon the door and lock for positively fastening the door in partly or entirely closed position, electrically operated means for holding the door locking means in engagement with each other during the flow of current to the motor, and cooperating means upon the car

and lock for automatically unlocking the door when the car is at the door and the current to the motor is cut off.

5. A lock for elevator doors including a housing, a member having a longitudinal series of teeth for attachment to a door insertible into the housing when the door is closed, separate contacts within the housing for electrical connection to the car switch, a lever fulcrumed in the housing, means carried thereby for engaging and closing the circuit between the contacts, means for releasing the door upon failure of current, and cooperating means upon the toothed member and the lever for electrically connecting the contacts positively when the toothed member is inserted into the housing and for automatically and positively breaking the connection between the contacts when the toothed member is withdrawn from the housing.

6. The combination with a housing for installation at an elevator landing, and a tongue attachment to a door at an elevator landing, said tongue having a longitudinal series of teeth and being insertible into the housing when the door is shut and having a slot, of a lever fulcrumed in the housing, a circuit closing member movably connected to the lever, contacts adjacent thereto adapted to be included in a circuit with the car switch of the elevator, a weight carried by the lever for holding said member normally spaced from the contacts, means carried by the weight for engagement by the slotted portion of the tongue when inserted into the housing to shift the lever positively and close the circuit between the contacts, said means cooperating positively to break the circuit between the contacts when the tongue is withdrawn from the housing.

7. The combination with a housing for installation at an elevator landing, and a tongue attachment to a door at an elevator landing and having a longitudinal series of teeth, said tongue being insertible into the housing when the door is shut and having a slot, of a lever fulcrumed in the housing, a circuit closing member movably connected to the lever, contacts adjacent thereto adapted to be included in a circuit with the car switch of the elevator, a weight carried by the lever for holding said member normally spaced from the contacts, means carried by the weight for engagement by the slotted portion of the tongue when inserted into the housing to shift the lever positively and close the circuit between the contacts, said means cooperating positively to break the circuit between the contacts when the tongue is withdrawn from the housing, a yieldingly controlled pawl for engaging the tongue to hold it in the housing when the door is partly or entirely closed, and electrically operated means controlled by the making and breaking of the circuits to the contacts, for respectively holding the

pawl in engagement with and releasing it from the tongue.

8. The combination with an elevator car, a motor for actuating the same, an enclosure, and a door at the elevator landing, of a tongue movable with the door and having a longitudinal series of teeth, a housing adjacent the landing for receiving the tongue when the door is closed, a pawl within the housing 10 for engaging the teeth when the door is partly or entirely closed, an electromagnet, means operated by the magnet when energized for holding the pawl against disengagement from the tongue, said magnet being 15 electrically connected to the motor so as to be energized during the operation of the motor,

a car switch for controlling the energizing of the motor, a switch within the housing for controlling the circuits to the car switch, cooperating means upon the tongue and lock 20 for thrusting said switch to closed position when the door is closed and for positively pulling the said switch to open position when the door is opened, and cooperating means upon the lock and car for automatically releasing the tongue and permitting the door to open when the motor is stopped and the magnet is de-energized. 25

In testimony that I claim the foregoing as my own, I have hereto affixed my signature.

MARTIN J. ROBERTSON.
